UNITED STATES PATENT OFFICE.

JAMES W. WOMELDORFF, OF MIDDLEPORT, OHIO.

RAILROAD-TICKET.

SPECIFICATION forming part of Letters Patent No. 286,101, dated October 2, 1883.

Application filed March 21, 1883. (No model.)

To all whom it may concern:

Be it known that I, JAMES W. WOMELDORFF, a citizen of the United States, residing at Middleport, in the county of Meigs and State of Ohio, have invented a new and useful Improvement in Railroad-Tickets, of which the following is a specification.

My invention relates to that class of railroad-tickets known as "through" or "coupon" tickets; and it has for its object to provide means whereby a single through-ticket may be adapted to pass one or more persons from one station to another over any one of a number of routes connecting the two stations. To this end my invention consists in the construction and combination of parts forming a railroad-ticket, hereinafter described and claimed, reference being had to the accompanying drawings, in which—

Figure 1 represents a four-route ticket, showing my invention; and Fig. 2, a modification of the same.

This ticket is adapted to pass one or more persons from Middleport to Chicago over either one of the four routes marked 1 2 3 4 on the agent's stub A. The ticket is perforated, as usual, to be torn off at cross-lines *a*, *b*, and *c*, the line *a* separating the agent's stub from the ticket, and line *b* separating the first ticket from the rest, &c. The section E of the agent's stub A is divided into four spaces marked 1 2 3 4, respectively indicating routes thus numbered, and these numbers are referred to by the agent in his communications with railway-officials in speaking or writing of said routes. These spaces may be made across the ticket, as in Fig. 1, or along the ticket, as in Fig. 2, and each of the coupons is divided into exactly similar spaces, so that when the ticket is folded at the lines *a* and *b* each space of the coupons will be directly under the corresponding space on the stub, so that if a certain space of the stub be punched when the ticket is thus folded its corresponding space on each coupon will also be punched. This feature is not broadly new; but I think the following is new: Each numbered space on the stub has printed on it the names or initials of all the roads forming one route between Middleport and Chicago, also the name of the junction of each road with the next in line of the route. The first

coupon, B, has printed on it in the respective spaces the names or initials of the first roads of all the routes and the names of their termini on the route, and the second coupon, C, 55 is similarly marked with the second roads of each route, &c.

The application is as follows: Suppose a traveler applies at the Middleport station for a ticket for Chicago. The agent takes one of 60 these tickets from the hook and informs the traveler that there are four roads over either of which he can go to Chicago. After hearing the routes named he elects, for example, to go by Fostoria, which is route 3. The agent then 65 folds the ticket, stamps through it at routes 1, 2, and 4, canceling them, and tears off the stub at *a*, thus preserving a memorandum of the ticket sold and the route over which it is used—to wit, the C., H. V., and T. to Fostoria, 70 and the B. and O. from Fostoria to Chicago. The ticket is first presented on the way from Middleport to Fostoria on the Columbus, Hocking Valley, and Toledo road, and the conductor of that road removes coupon B, which is 75 printed at one end, *e*, showing that it was issued by his road—the C., H. V., and T.—to pass also over the B. and O. The next coupon will be taken up by the B. and O. road, showing that it carried a passenger for the C., H. V., and 80 T. road from Fostoria to Chicago. In the same manner either one of the other routes might have been selected at first by the traveler, and the same ticket, differently canceled, would have passed him. At the same time the stub and 85 coupons, all canceled alike, preserve a complete record of the transaction for final settlement between the different roads of the route. One ticket may be thus printed to represent any number of routes, and if any route had a less 90 number of roads than the others a corresponding number of coupons would be left blank in its line to be torn off by the agent who sold it.

Some of the advantages of this invention are that a ticket-agent, without any effort of memory or previous experience, may at once answer the traveler's questions as to routes to any point and the junctions or changes by merely examining the stub of a ticket covering all routes to that point, whereas by the old method he would have to examine as many tickets as there were routes in order to give 95 100

the same information, or, what is more common, refer to a railway guide for information; secondly, one union-ticket would be printed covering several routes, where formerly a separate ticket was printed for each route. This ticket may be used as an addition to some forms of tickets now in use—as, for instance, to the one shown in Patent No. 204,174.

I am aware that there are tickets somewhat like mine in use in which the agent's stub and each succeeding coupon indicate the place of departure and destination and road or roads over which the passenger will travel; but the succeeding coupons in my ticket do not necessarily show either the place of first departure or the place of final destination, and I do not claim the same; but

What I claim is—

1. A railroad coupon-ticket having on the agent's stub separate spaces, each space indicating a different route between two points or stations, in combination with coupons adapted

to be folded beneath said stub, each coupon having two or more routes marked on it corresponding to those on the agent's stub, as shown and described, whereby one ticket is adapted for use over either one of two or more routes. 25

2. The stub A, having two or more spaces, 1, 2, &c., in which are marked the names or initials of the roads forming different routes between two stations, and the names of stations where said roads join, in combination with one or more coupons, B C, having spaces corresponding to the stub, each coupon being marked for one road, with its terminal stations of each of said routes, and the consecutive coupons representing the roads of all the routes in their consecutive order from the starting-point, as shown and described. 30 35
